ADJUSTABLE BACK BOX PLATE

Carl D. Brown, Hopedale, Mass., assignor to
Draper Corporation, Hopedale, Mass., a corporation of Maine

Application December 12, 1940, Serial No. 369,851

6 Claims. (Cl. 139—183)

This invention pertains to shuttle boxes for fly shuttle looms and more particularly relates to devices for aligning the back box plate of the shuttle box with the reed.

Looms of the type to which my invention applies commonly include a lay beam carrying a reed, a supporting member or sword, and a shuttle box at each end of the lay beam, such shuttle box including a shuttle guiding member adapted to be aligned with the reed. Alignment 10 of the shuttle guiding member and the reed must be quite accurate and realignment may be required whenever a different reed is installed in the loom.

It has been proposed to adjustably secure the 15 shuttle guiding member to the supporting member by means of a plurality of positioning screws threaded into one of said members and projecting therefrom for engaging the other member and fastening means threaded into the shuttle guiding member and extending through an opening in the supporting member. Thus by properly adjusting the positioning screws and fastening means the shuttle guiding surface could be accurately aligned with the reed. However, in such construction I find that the ends of the 20 positioning screws will over a period of time wear holes in the supporting member to such an extent as to make proper adjustment of the shuttle guiding member extremely difficult.

Accordingly, it is a principal object of the present invention to provide in a loom including a lay beam carrying a reed, a supporting member and a shuttle box including a shuttle guiding member adjustably attached to the supporting member by means of positioning screws and fastening means as aforesaid, a plate positioned between the shuttle guiding member and the supporting member and adapted to be engaged by the ends of said screws, said plate being rotatably mounted whereby upon rotation thereof a new surface is brought into engagement with the end of each screw.

The foregoing and other objects of the invention are accomplished in the construction illustrated in the accompanying drawing, of which:

Fig. 1 is a plan view of a portion of the right hand end of the lay;

Fig. 2 is a front view of a portion of the lay and the inner end of the shuttle box, and

Fig. 3 is a view in perspective of the rotatable plate.

The drawing shows but part of a loom having my invention applied thereto, the parts and mechanisms not shown being of any suitable usual construction and forming no part of the present invention. The drawing shows a portion of the right hand end of the usual lay beam 1 which is fixed to the front face of a sword 2. The lay beam 1 carries a reed 3 and a shuttle 60

box indicated generally at 4. The shuttle box shown on the drawing is the right hand shuttle box and only a portion of the inner end of the box is shown. The shuttle box shown comprises a floor 5, a front box plate 6, a back box plate 7 and a top shelf 8.

The particular back box plate shown is constructed of two separate members, the outer end or member 8' being relatively fixed to the lay beam (the point of attachment not being shown) and the inner end or member 9, which carries the shuttle guiding surface 10 being adjustable. The two members may be connected together by a universal joint indicated generally at 11 and more fully disclosed in patent to W. I. Stimpson No. 1,848,674 granted March 8, 1932.

The universal joint connection permits the inner end member 9 to be adjusted about different axes, one extending horizontally longitudinally of the lay and shuttle box and the other extending vertically.

In other words the shuttle guiding member 9, carrying the shuttle guiding surface 10, may be tilted about a horizontal axis to bring the shuttle guiding surface into a plane parallel with the reed and may be moved bodily forwardly or rearwardly transversely of the lay beam to bring the shuttle guiding surface into horizontal alignment with the reed.

The inner end or shuttle guiding member 9 of the back box plate is attached to the sword 2 by means which can be manipulated to produce the desired adjustment of the shuttle guiding surface, the member being firmly fixed in position after the adjustment is accomplished.

Such adjusting means may comprise suitable fastening means such as a threaded member or cap screw 12 extending through a vertical elongated opening 13 in the sword 2 and threaded into an opening 14 in the inner end of member 9. The cap screw 12 is of such length that it cannot project beyond the shuttle guiding surface 10. A plate 15 made of hard metal or any other suitable material is loosely mounted on cap screw 12 between the member 9 and the sword 2 for a purpose hereinafter to be described. The plate 15 is shown on the drawing as having a square shape, however plate 15 may be round or polygonal, the essential being that plate 15 be of such size and shape as to be rotatable on cap screw 12. A plurality of adjusting screws are threaded into the inner end of member 9 and project therefrom for engagement with plate 15. On the drawing three such screws 16, 17 and 18 are shown. Each of screws 16, 17 and 18 is offset radially at different distances from the axis of rotation of the cap screw 12. Each of screws 16, 17 and 18 is provided with a hexagonal depression in the head thereof to facilitate adjustment. As shown on Fig. 2 screw 16 is located

below the cap screw 12, screw 17 is located above the cap screw 12 and screw 18 is located in substantial horizontal alignment with cap screw 12.

Thus it will be seen that by proper adjustment of the screws 16, 17 and 18 the member 9 may be tilted about a horizontal axis to bring the shuttle guiding surface 10 into a plane parallel with the reed and by turning cap screw 12 the member 9 may be moved bodily forwardly and rearwardly transversely of the shuttle box to bring the shuttle guiding surface into horizontal alignment with the reed. After the member 9 has been properly adjusted the assembly may be locked in adjusted position by tightening up on cap screw 12.

The pressure of the ends of the screws 16, 17 and 18 on plate 15 will over a period of time wear holes in plate 15. When this condition exists proper adjustment of the member 9 is extremely difficult. However, as plate 15 is rotatably mounted on cap screw 12, it may be revolved to bring a new surface into contact with the ends of the screws 16, 17 and 18. After all of the surface on one side of plate 15 has become worn it may be removed and reversed thereby providing new surfaces for engagement with the screws.

As the screws 16, 17 and 18 are offset radially at different distances from the longitudinal axis of cap screw 12, it is impossible upon rotation of plate 15 for one screw to engage the same surface of plate 15 as was previously engaged by another screw.

Having thus fully disclosed the preferred embodiment of the invention, I claim:

1. In a loom, a lay having a reed along which a shuttle may run, a shuttle guiding member independent of the reed supported by said lay, a member for supporting said lay and to which said first named member is adjustably attached, a plurality of screws carried by one of said members, said screws extending and movable transversely of the reed to position said shuttle guiding member relatively to the reed, a plate positioned between said members and against which the points of said screws bear, and fastening means extending through one of said members and said plate, said plate being rotatable about said fastening means to bring new bearing surfaces into contact with said points of said screws, said fastening means being threaded into the other of said members for moving said guiding member transversely of the lay and for locking said members together.

2. In a loom, the combination of a lay including a reed, a sword for supporting said lay, a shuttle box mounted on said lay and having a back box plate including an inner end adapted to be aligned with said reed, adjustable fastening means connecting said sword and said inner end of said box plate for moving said box plate transversely of said reed, a rotatable plate loosely mounted on said fastening means and interposed between said box plate and said sword and a plurality of adjustable screws threaded into said box plate and extending therethrough into engagement with said plate, said screws acting to position said box plate with respect to said reed.

3. In a loom, the combination of a lay having a reed, a shuttle guiding member independent of the reed supported by said lay, a member for supporting said lay and to which said first named member is adjustably attached, a plurality of

adjustable screws threaded into and projecting from one of said members, said screws extending and movable transversely of the reed to position said shuttle guiding member relatively to the reed, a plate rotatably mounted between said members and against which plate the points of said screws bear, and a threaded member extending through said supporting member and said plate and threaded into said guiding member for locking said members together, each of said screws being spaced radially at different distances from the longitudinal axis of said threaded member whereby upon rotation of said plate a new bearing surface is brought into contact with the points of each of said screws.

4. In a loom, a lay including a reed and a shuttle box having a back box plate adapted to be aligned with the reed, a sword for supporting said lay, said sword having an opening therein, a plate of hard metal interposed between said sword and said back box plate, said plate having an opening therein, a plurality of adjustable screws threaded into and projecting from said box plate into engagement with said plate and a threaded member extending through said openings in said sword and said plate and threaded into said box plate for locking said members together, said plate being rotatable about said threaded member and each of said screws being offset radially at different distances from the longitudinal axis of said threaded member whereby upon rotation of said plate a new bearing surface is brought into contact with the ends of each of said screws.

5. In a loom, a lay including a reed and a shuttle box having a back box plate adapted to be aligned with the reed, a sword for supporting said lay, said sword having a vertically elongated opening therein, a threaded member carried by said sword extending through said opening and threaded into said back box plate for moving said box plate transversely of said reed and about a horizontal axis in relation to said reed, a plurality of adjustable screws threaded into and projecting rearwardly from said box plate toward said sword, and a hardened metal plate interposed between said sword and said screws and against which said screws bear, said plate being mounted on said threaded member for rotation about the axis of the latter to bring a new bearing surface into contact with said screws.

6. In a loom, a lay including a reed and a shuttle box having a back box plate adapted to be aligned with the reed, a sword for supporting said lay, said sword having an opening therein, a cap screw carried by said sword and extending through said opening and threaded into said back box plate for moving said box plate transversely of said reed and about a horizontal axis in relation to said reed, a plurality of adjustable screws threaded into and extending from said box plate toward said sword, at least one of said adjustable screws being located above said cap screw and at least one of said adjustable screws being located below said cap screw, and a plate of hard metal interposed between said sword and said adjustable screws and against which the points of said adjustable screws bear, said plate being rotatably mounted on said cap screw whereby upon rotation of said plate a new bearing surface is brought into contact with each of the points of said adjustable screws.
